ACCESSORY BRACKET FOR A CAMERA OR SIMILAR ARTICLE

William R. Mechnick, 72 Evergreen Ave.,
New Providence, N.J.

Filed Dec. 31, 1962, Ser. No. 72,993

Term of patent 14 years

(Cl. D61—1)

The essential features of my new design reside in the portions shown in full lines.

I claim:

The ornamental design for an accessory bracket for a camera or similar article, as shown and described.
